UNITED STATES PATENT OFFICE.

THOMAS W. BRACHER, OF NEW YORK, N. Y.

SWEAT-BAND FOR HATS.

SPECIFICATION forming part of Letters Patent No. 367,266, dated July 26, 1887.

Application filed October 14, 1886. Serial No. 216,262. (No model.)

To all whom it may concern:

Be it known that I, THOMAS W. BRACHER, a citizen of the United States, residing at New York, in the county and State of New York, 5 have invented new and useful Improvements in Sweat-Bands for Hats and Caps, of which the following is a specification.

This invention consists in a sweat-band having a reed or spring on its under side near the edge, secured in position by binding-stitches. The binding-threads have their interlocked portion at the extreme edge of the sweat-band, so as to cover said edge and provide a means for conveniently securing the sweat-band in 15 the hat or cap.

My invention is illustrated in the accompanying drawings, in which Figure 1 represents a face view of a portion of a sweat-band constructed according to my invention. Fig. 2 is a rear view of the same. Fig. 3 is a top edge view of the same. Fig. 4 is an enlarged view of the stitch which may be used in forming my sweat-band. Fig. 5 is a section of a portion of a hat provided with my sweat-band.

Similar letters indicate corresponding parts.

In the drawings, the letter A designates a sweat-band for a hat or cap. B is the spring or reed, the object of which is to retain the 30 distended or flaring edge of the sweat-band in position.

By referring to Figs. 1, 2, and 5 it will be seen that the spring or reed B is situated on the inner side of the sweat-band A, and it is 35 retained in position by a series of binding-stitches formed by means of two or more threads. In the example represented in the drawings, the binding stitches are formed by two threads, a and b, the thread a being passed 40 and repassed through holes c in the sweat-band in such a manner that they form an imitation of handlashing stitches on the face of

the sweat-band, (see Fig. 1,) while on the back or inner side said thread a follows a zigzag course, as seen in Fig. 2. The thread b is interlaced with the thread a in the manner shown in Fig. 4, and if the stitches are drawn tight the interlocking portions of the two threads are situated over the outer edge of the sweat-band, or nearly so, (see Fig. 3,) so that they 50 practically conceal said edge, and at the same time they form a very convenient medium for securing the sweat-band to the hat. From this explanation it will be perceived that the binding-stitches serve three different purposes— 55 first, to cover the raw edge of the sweat-band by having the interlocking portions of the threads placed thereon; second, to form an excellent medium for securing the sweat-band to the hat; third, to bind the spring or reed 60 on the under or inner side of the sweat-band.

In my sweat-band the spring, being on the inner side of the sweat-band, is concealed, and when the sweat-band is secured in a hat or cap said spring is not liable to produce a 65 mark on the forehead of the person wearing the article.

What I claim as new, and desire to secure by Letters Patent, is—

A sweat-band for hats and caps, having a 70 thread, b, running along and covering the raw edge thereof, a spring secured directly to said band near the edge by thread a, passing through the band and over the edge thereof and interlocking with the thread b, whereby a continuous 75 protecting-cover is formed for the raw edge of said band, substantially as described.

In testimony whereof I have hereunto set my hand and seal in the presence of two subscribing witnesses.

THOS. W. BRACHER. [L. s.]
